UNITED STATES PATENT OFFICE.

PILADE BARDUCCI, OF MILAN, ITALY.

DRYING PLANT.

Application filed October 8, 1923. Serial No. 667,382.

To all whom it may concern:

Be it known that I, PILADE BARDUCCI, subject of the King of Italy, residing at Milan, Italy, and temporarily at Naples, Italy, have invented certain new and useful Improvements in Drying Plants, of which the following is a specification.

The present invention relates to drying plants of the kind in which the air is agitated by means of propellers producing a vertical air current and caused to travel with respect to the material to be dried; it has for its object an apparatus by means of which the air is agitated within a room in an efficient and even manner, the said apparatus being at the same time of a simple and compact construction.

In plants of known construction in which the air is agitated by means of propellers free in the room and carried by a travelling carriage, said propellers must have a large diameter and extend substantially throughout the span or width of the room in order to act evenly on the material located in the same; this fact produces the drawback that the air currents produced by such large propellers have a quite different intensity in their several portions and air streams are directed towards the room walls; further, in view of the propeller size, the travelling carriage is not steady in its running.

The present invention has for its object an apparatus in which said drawbacks are removed.

The apparatus according to the present invention comprises a travelling member or carriage which is provided with one or more hopper-shaped or tapering casings in each of which is located an air propeller of comparatively small size. Said casings are elongated in a direction transverse with respect to the carriage path and they are arranged at the side of each other to extend substantially through the whole span or width of the room in which the apparatus is located.

Each propeller is mounted at or near the smaller mouth of its casing for improving the air flow therearound.

On the annexed drawing is illustrated by way of example an embodiment of the present invention and Figure 1 is a longitudinal section of a drying chamber provided with an air agitating apparatus according to the present invention; Figure 2 is a transverse

section of the same on line 2—2 of Figure 1, and on a larger scale; Figure 3 is a plan view of the said air agitating apparatus and Figure 4 is a transverse section of a room with a modified construction of air agitating apparatus.

In said drawings, 1 is a drying chamber provided with an inlet mouth 2 and an exhaust mouth 3 having an air propeller 4. On rails 5 located in said room reciprocates an air agitating apparatus hereinafter described, which is adapted to produce a strong air current in the space in front of the material to be dried, which is assumed to be located in the space enclosed between chain lines, being thus subjected to an intermittent ventilation.

The air agitating apparatus comprises a carriage 7 having wheels 8 for reciprocation on rails 5 and casings 9—9 are located on said carriage, each having the shape illustrated on the drawing, that is comprising a frame 13 in which is located a propeller 10, front and rear walls 14 and side walls 15 which are inclined with respect to the propeller axis; each casing has thus a tapering outline in its transverse section as shown by Figure 2.

Each casing is arranged with its front and rear walls 14 transverse to the path of travel of the carriage, while the side walls 15 are in the direction of said path, while being inclined with respect to the axis of the air propeller 10. Each casing has thus a smaller mouth encircling the propeller and having substantially the same size as it, and a larger mouth which is elongated in a direction transverse to the path of travel of the apparatus.

The casing 9 is supported on the carriage 7 by means of uprights 12 leaving a free space in the rear of the frame 13 for the free flow of air from the mouth encircling the air propeller 10.

Means may be provided in the larger mouth to obtain an even air flow throughout its extent, as a row of blades spaced apart to different extents, or a metal grid 16 having meshes of different size as shown in Fig. 4.

The carriage is driven in the known manner by means of an electromotor 17 actuating the shaft 18 of wheels 8.

When the propellers 10 are driven by the electromotor 11 a suction is produced within the casings 9, which acts to an even extent

throughout their top mouths, with a ridge, one or more funnel-shaped casings 45 carried by said carriage, each casing having a mouth on its bottom, and air agitating means located in said mouths.

5 the casings 9, as shown by arrows in Figures 2 and 3.

Of course the propellers may also be operated in reverse direction than assumed in the drawing, and then they draw air from 10 the lower mouths and propel it upwards, the flow of air around the casings 9 having in this case a downward direction.

Owing to the shape of the casings through which the air agitation is produced, 15 the propellers may have a smaller size than in known constructions and thus their arrangement in the carriage is made easy and the carriage may be more light, small and stiff than in known arrangements.

20 Figure 4 shows a drying room according to the present invention in which the casing carriage is mounted to move near the room roof and the material is arranged below it, in the space enclosed within chain lines.

25 Of course many modifications may be introduced in the described apparatus without coming out of the spirit of the present invention as defined by appended claims; more particularly the carriage may carry a 30 single one or any number of casings 9 each with a propeller, being only essential that said casing or casings provide an elongated mouth opposite the material and extending substantially throughout the space occupied 35 by the same material.

What I claim as my invention and desire to secure by United States Letters Patent is:—

1. In a drying chamber, a travelling carriage, one or more casings carried by said carriage, each casing having its bottom shaped as a mouth, and air agitating means located in said mouths.

2. In a drying chamber, a travelling car-

riage, one or more casings having lateral 50 walls diverging from the bottom of the same, each bottom providing a mouth, and air agitating means located in said mouth.

3. In a drying chamber, a travelling carriage, one or more casings carried by said carriage, each casing having a mouth opening in front of the space for the material and a second mouth smaller than the 60 first one and joined thereto, and agitating means located in said second mouth.

4. In a drying chamber in which the material to be dried is located in the middle 65 zone between the roof and the floor, a travelling carriage, one or more casings carried by said carriage, each casing having a mouth elongated in a direction transverse to the path of travel of said carriage and opening in front of the space for the material, a 70 second mouth smaller than the first one and joined thereto, and agitating means located in said second mouth.

5. In a drying chamber in which the material to be dried is located in the middle 75 zone between the roof and the floor, a travelling carriage, one or more casings carried by said carriage, each casing having a mouth opening in front of the space for the material, a second mouth smaller than the first one 80 joined thereto and at a distance from the opposite horizontal wall of the chamber, and agitating means located in said second mouth.

6. In a drying chamber in which the material to be dried is located in the middle 85 zone between the roof and the floor, a travelling carriage, one or more casings carried by said carriage each casing having a mouth opening in front of the space for the material, a second mouth smaller than the first one joined thereto and at a distance from the opposite horizontal wall of the chamber, and agitating means located in said second mouth.

In testimony whereof I have signed my 85 name to this specification.

PILADE BARDUCCI.
